INVENTOR

Archie P. Clark,

BY *Richard Oliver,*

ATTORNEY

UNITED STATES PATENT OFFICE.

ARCHIE PAUL CLARK, OF ALVASTON, BRITISH COLUMBIA, CANADA.

SHELL.

Specification of Letters Patent. Patented Aug. 13, 1918.

1,275,660.

Application filed April 23, 1917. Serial No. 164,058.

To all whom it may concern:

Be it known that I, ARCHIE PAUL CLARK, a citizen of the United States, residing at Alvaston, in the Province of British Columbia and Dominion of Canada, have invented certain new and useful Improvements in Shells, of which the following is a specification.

This invention relates to improvements 10 in projectiles, and more particularly to those used in heavy ordnances.

The main object of the invention is to provide a simple and cheaply constructed projectile which is adapted to discharge a 15 plurality of smaller projectiles with a maximum amount of force and a minimum consumption of powder.

Another object is to provide a projectile 20 in the form of a shell which is rendered doubly safe by the use of a visible fuse and in which it is necessary to fire the powder before the discharge will occur.

Another object is to provide a shell of 25 this character which is equipped with means to prevent cutting off of the fuse should the shell penetrate a solid object.

With the foregoing and other objects in view, which will appear as the description proceeds, the invention resides in the combination and arrangement of parts and in the details of construction hereinafter described and claimed, it being understood 30 that changes in the precise embodiment of the invention herein disclosed may be made 35 within the scope of what is claimed without departing from the spirit of the invention.

In the accompanying drawings:

Figure 1 represents a side elevation of a shell constructed in accordance with this invention.

Fig. 2 is a central longitudinal section thereof,

Fig. 3 is a transverse section taken on the line 3—3 of Fig. 1,

Fig. 4 is a side elevation on a small scale with parts broken out, and

Fig. 5 is a detail showing slightly different means for retaining the bullets in the firing chambers, the casing being omitted.

The body 1 of the shell constituting this 50 invention is constructed of ordinary configuration and of any suitable metal, preferably iron or steel, in cylindrical form and with a pointed end or nose 2. A bore 3 extends longitudinally through the center of the body portion 1, from end to end there-

of, and the portion of said bore which extends through the nose of the shell is threaded to receive a closure in the form of a threaded plug 4 having a hand grip 5 at its outer end to facilitate its insertion and removal. The other end of the bore 3 at the rear of the shell is closed by a cap 6 which preferably fits within a fragile jacket or casing 7 composed of tin or other readily penetrable material which is fitted over the shell to retain the smaller projectiles to be described within the firing chambers. A plurality of longitudinally spaced series of bores or openings 8 radiate from the bore 3, four of said openings 8 being here shown in each series, but obviously any desired number may be used, and eleven series of these bores are shown but it is obvious that this number may be increased or decreased 75 at the will of the manufacturer. These bores or openings 8 may be of any desired caliber according to the size of the bullets or projectiles 9 which are to be loaded therein. As shown, these bores taper toward 80 their inner ends as indicated at 10, each being connected with the bore 3 by a tubular neck 11. These necks are designed to receive a fuse of slow burning powder for igniting the charge or explosive indicated 85 at 12 therein, said explosive being preferably powder. Arranged outside the explosive charge 12 in each bore 8 are a plurality of bullets 9, three of which are here shown disposed in each opening 8, said openings 90 constituting firing chambers.

A slow burning powder or fuse 13 is disposed within the bore 3, being retained therein by the threaded plug or rod 4 mounted in the nose 2 and which is designed to be 95 removed to permit charging of this bore.

A fuse opening or channel 14 opens through one side wall of the body member 1 near the pointed end thereof, and communicates with bore 3 and is designed to 100 receive and house a fuse 15, one end of which is embedded in the powder or fuse 13 in bore 3 and the other end of which projects beyond the larger rear end of the shell as is shown at 16, said fuse being arranged 105 between the frangible jacket 7 and the outer face of the body 1 of the shell.

From the above description, it will be seen that when this shell is loaded in the manner above described, the firing chambers 8 thereof being connected through their necks 11 with the fuse chamber 3, that the ignition of

the fuse 15 will cause the powder or fuse 13 to ignite and fire the charges 12 contained in the chambers 8, said explosion in the chambers occurring at intervals during the flight 5 of the projectile, thus discharging the bullets 9 over a large area.

Hence it will be obvious that by so constructing this projectile that a large number 10 of bullets may be carried and discharged thereby according to the caliber of the firing chambers and the number of bullets employed. It will also be seen that the charge 12 of each firing chamber 8 which is comparatively small in quantity, will yet be sufficient 15 to fire these bullets at a high velocity thereby greatly cheapening the construction of the shell.

It will also be understood that the countersinking of the fuse 15 at one side of the nose 20 2 of the projectile will prevent all possibility of the fuse being cut off should the projectile penetrate a solid object, and hence the explosion of the shell will not be interfered with.

25 While the bullet retaining casing 7 has been shown in connection with this shell, it is to be understood that this casing is not an essential feature of the invention and may be dispensed with, the bullets being retained 30 within their firing chambers by crimping the ends of the chambers over them after they have been loaded, and this form is shown in detail in Fig. 5.

From the foregoing description, taken in 35 connection with the accompanying drawings, the advantages of the construction and of the method of operation will be readily apparent to those skilled in the art to which the invention appertains and while I have described 40 the principle of operation of the invention together with the device which I now consider to be the best embodiment thereof, I desire to have it understood that the device shown is merely illustrative and that such 45 changes may be made as are within the scope of the claimed invention.

I claim:

1. A projectile of the class described comprising a solid body member having a bore 50 extending longitudinally throughout with firing chambers radiating therefrom at right angles thereto and communicating therewith

and adapted to receive explosive material and small projectiles, a fuse disposed in said bore and connected with the firing chambers, 55 and a fuse housed in one end of said body member connected with the fuse in said bore in advance of said chambers and extending through one side wall of said body member, and countersunk therein to prevent cutting 60 off of the fuse when the projectile enters a solid object.

2. A projectile of the class described comprising a solid metal body having a pointed nose and a central fuse-containing bore extending longitudinally from end to end 65 thereof, the portion passing through said nose being threaded, a closure plug having threaded engagement with said threaded bore and, a plurality of longitudinally spaced 70 series of branch bores radiating from said central bore and opening through the side walls of said body to form firing chambers, channels of reduced diameter connecting the inner ends of said chambers with said central 75 bore and adapted to receive fuses which connect the firing chambers with the central bore, bullets arranged in said chambers, a frangible jacket encircling said body, and closing said chambers, and a fuse leading 80 from one end of said central bore.

3. A projectile of the class described comprising a solid metal body having a pointed nose and a central fuse-containing bore extending longitudinally from end to end 85 thereof, a plurality of longitudinally spaced series of branch bores radiating from said central bore and opening through the side walls of said body to form firing chambers, said chambers tapering toward their inner 90 ends, channels of reduced diameter connecting said ends with said bore, and a fuse channel opening through one side wall of the body near its nose and communicating with said central bore, said fuse channel being 95 countersunk in said body to prevent the fuse being cut off when the shell enters a solid object.

In testimony whereof I affix my signature in presence of two witnesses.

ARCHIE PAUL CLARK.
